(57) **CLAIM**

The ornamental design for a display stand base, as shown and described.

DESCRIPTION

FIG. 1 shows a front perspective view of a display stand base. FIG. 2 shows a rear perspective view of the display stand base. FIG. 3 shows a front view of the display stand base. FIG. 4 shows a rear view of the display stand base. FIG. 5 shows a right side view of the display stand base. FIG. 6 shows a left side view of the display stand base. FIG. 7 shows a top view of the display stand base. FIG. 8 shows a bottom view of the display stand base; and, FIG. 9 shows a rear perspective view of the display stand base with optional poster paper and pole.

In the drawings, the broken lines in the figures illustrate environment and form no part of the claimed design.

The design relates to a display stand base. Essentially the display stand base is for a type of free-standing roll up display system or easy roll display system for exhibition use, for example. The display stand base may act as a container for the print (poster paper for example) to be displayed, which may roll into it. The print may be pulled out from the display stand base for display and then held in place by a pole secured in the display stand base. The display stand base may also be used in other type of display systems.
